(57) **CLAIM**

The ornamental design for a pair of beach pants, as shown and described.

DESCRIPTION

FIG. 1 is a front, right, and top perspective view of a pair of beach pants, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view of a first state; and,

FIG. 10 is a perspective view of a second state.

The broken lines shown in the drawings are included for the purpose of illustrating portions of the pair of beach pants that form no part of the claimed design.

The broken lines of the humanoid figure in FIGS. 9 and 10 depict environment that form no part of the claimed design.
